Inventor

UNITED STATES PATENT OFFICE.

MARK DEAN, OF BOONVILLE, NEW YORK.

SIGNAL-OPERATING DEVICE FOR AUTOMOBILES.

1,351,745.

Specification of Letters Patent. Patented Sept. 7, 1920.

Application filed May 18, 1918. Serial No. 235,260.

To all whom it may concern:

Be it known that I, MARK DEAN, a citizen of the United States, and a resident of Boonville, Oneida county, and State of New York, have invented certain new and useful Improvements in Signal-Operating Devices for Automobiles, of which the following is a specification.

The object of my invention is to provide means whereby an electric push button or any other mechanism employed to sound a horn or to give or display any other form of signal, can be operated more easily, and effectively, than heretofore.

My invention will, naturally, be applied more particularly to automobiles because the giving of a warning signal has to be done more or less suddenly when occasion arises and if possible without interrupting the work of hands or feet in operating the car. But it is also applicable to all cases where simple pressure can best be utilized for giving a signal or alarm without attracting or diverting attention.

Various mechanical devices can be employed embodying my invention which consists broadly in providing an easily operated pressure arm or rod located within easy reach of the operator and adapted to be thrown quickly into contact with a signal-giving mechanism and thus cause the same to act immediately in giving said signal.

In the accompanying drawings:

Figure 1, is a front elevation of one form 35 of my improved device.

Fig. 2, is a top plan thereof.

Fig. 3, is a detail of the adjustable swivelled bracket.

Fig. 4, is a front elevation of a modified 40 form of my improved device.

Fig. 5, is a top view thereof.

Fig. 6, is a detail of the swivel head thereof.

Same letters indicate similar parts in the 45 different figures.

A is a portion of the car-door. B, is a portion of the sidewall of the car. C, is a rod located horizontally across the car door within easy reach of the knee of the operator, as shown in Fig. 4, or lower down as shown in Fig. 1, to permit of the upper knee-rod L standing at the knee level. D

is an off-set arm at the end of the rod C which may be used, as in the device shown in Figs. 1 and 2, to contact with the push button for other signal starting device or, as shown in Figs. 4 and 5 merely to serve as a stop to further movement of the rod.

Taking up the modification shown in Figs. 4 to 6, E is a swivel-head which serves as a connecting link between the rod C and the lever yoke F or other part of the signal starting mechanism. The rod C, therefore, in this case may hang simply supported by the swivel-head and be turned up out of the way when the car door is opened.

Turning to the form shown in Figs. 1 to 3 the rod C is supported on the car door itself by the fixed bracket c and a swivel stop bracket d. Upon this rod are two collars of which collar I is attached to the rod by the pin i and is therefore fixed. The other collar K is a sliding or adjustable collar, held in place by the set screw k when adjusted to the desired position.

From these collars rise respectively the uprights H, J, which terminate at the top in horizontal portions facing each other and adapted to enter the bore of the upper knee-rod L, in which they are moved slidably to 70 secure the desired length of the device so that the knee of the operator or some part of his leg is sure to strike either the uprights or the intervening upper rod.

It is obvious that pressure applied, by the 85 knee or otherwise, upon the rod L, or the uprights H, J, toward the door will turn the rod C in the same direction and thus contact the off-set arm D into operating contact with the signal starting device.

To limit the motion of the rod C and off-set arm D in either direction, a stop M is swiveled on the bracket b before referred to and adjustably fixed by the set screw a.

As before stated the purpose of this knee-rod, as I have called it, in all cases is to have an easily operated pressure device conveniently located between the operator and a fixed part of the signal giving mechanism so that in case it becomes necessary to sound 100 the horn or give other warning or signal while the hands and feet of the operator are otherwise occupied in manipulating the car a slight and almost unconscious movement

of the knee nearest the knee-rod will operate the signal giving device. But, obviously, other devices than knee-rods can be used for this purpose. Therefore

5 I claim:—

A knee switch for automobiles which comprises a rod rotatably mounted upon the side door of an automobile, and provided with an offset arm adapted to contact with

a signal giving mechanism, adjustable sleeves mounted on said rod and a pressure bar mounted upon said sleeves and located within easy reach of the knee of the operator.

MARK DEAN.
